No. 733,736.

PATENTED JULY 14, 1903.

H. H. NORRINGTON.
MANIFOLDING DEVICE.
APPLICATION FILED OCT. 3, 1902.

NO MODEL.

UNITED STATES PATENT OFFICE.

HENRY H. NORRINGTON, OF WEST BAY CITY, MICHIGAN.

MANIFOLDING DEVICE.

SPECIFICATION forming part of Letters Patent No. 733,736, dated July 14, 1903.

Application filed October 3, 1902. Serial No. 125,789. (No model.)

To all whom it may concern:

Be it known that I, HENRY H. NORRINGTON, a citizen of the United States, residing at West Bay City, county of Bay, State of Michigan, have invented a certain new and useful Improvement in Manifolding Devices, of which the following is a specification, reference being had to the accompanying drawings, which form a part of this specification.

10 My invention has for its object a manifolding device; and it consists of the features of construction hereinafter described and claimed, and illustrated in the accompanying drawings, in which—

15 Figure 1 is a view in perspective showing features of my invention. Fig. 2 is a similar view illustrating a modification of the same. Fig. 3 is a plan view of the device shown in Fig. 1. Fig. 4 is a view in section 20 on the line 4 4, Fig. 3. Fig. 5 is a view in section on the line 5 5, Fig. 4, looking in the direction of the arrow. Fig. 6 is a view in section on the line 6 6, Fig. 4, looking toward the bracket. Fig. 7 is a detail view of the 25 removable carbon roller.

The carbon-sheet in my present invention is rigidly attached to the roller, so that in renewing the carbon-sheet a new roller with the carbon-sheet attached is simply inserted 30 into the brackets, means being provided for suitably holding the roller in place and permitting the carbon to be unrolled therefrom. Obviously the insertion of a carbon-sheet in a roller or the engagement thereof with the 35 roller each time the carbon-sheet is to be renewed is an inconvenient matter, liable also to soil the hands and necessitating care and time in the transaction. One aim of my invention is to dispense with the necessity of 40 engaging the carbon-sheet with the roller when the sheet is to be replaced, the carbon-sheets being supplied to the user already mounted upon a roller.

In carrying out my invention, *a* denotes a 45 base, and *b* a cover therefor, the cover being reversible to have either side uppermost when opened or closed, the cover being connected with the base by swinging arms *c*, jointedly connected with the cover toward 50 the longitudinal center thereof, as at *d*. A revolving shaft or roller is indicated at *e*, journaled in brackets *g* and *h*, supported upon

the base, said roller provided with a carbon-sheet of any desired length, mounted and rolled thereupon, the carbon-sheet being indicated at *i*. The carbon-sheet may be engaged upon the roller in any suitable manner. The bracket *g* to receive one end of the roller is recessed upon its upper surface, as at *j*, to receive the corresponding end of the roller. Over the bracket *g* is a hinged cover *k*, provided with a pin or stud *l* to set down into an orifice *m* in the adjacent end of the roller to hold the roller in position. The opposite end of the roller is engaged in bracket *h*, which is constructed with an orifice *n* to receive the end of the roller. A screw *p* enters the end of the roller to hold it in place, the screw also serving as a head whereby to rotate the carbon roller.

Upon the base *a* is secured in any suitable manner a series of blanks or sheets *q*, over each of which the carbon-sheet may be drawn into position for making a carbon copy of any writing upon one of the blanks. Upon one surface of the cover is engaged, also in any suitable manner, a series of sheets or blanks of paper, (indicated at *r*), being readily detachable one from another, to be placed over the carbon-sheet *i* when drawn out over the upper sheet or blank of the series *q*. In this manner a copy of the writing on the sheet *r* thus placed in position may readily be made upon one of the sheets *q*. The carbon copy may then be readily detached and another sheet *r* be placed over the carbon-paper for a subsequent carbon copy. My present invention provides also a holding-bar, (indicated at *s*), having its extremities engaged with the inner surfaces of the brackets *g* and *h*. I prefer that the engagement of the holding-bar with said brackets should be adjustable, and to this end the inner surfaces of the brackets are provided with sockets *t*, into which the adjacent extremities of the holding-bar may be entered. This holding-bar will aid in keeping the carbon-sheet in proper position and at the same time it serves as a guide-bar in placing the sheets *r* in place for making the carbon copy. The holding-bar is preferably constructed to extend forward of the brackets, and it will readily drop into position by gravity.

As indicated in Figs. 1 and 3, the arms *c* on

the cover at their outer extremities are engaged with the adjacent brackets *g* and *h*. In the form shown in Fig. 2, where the cover opens at the side of the base *a*, one of the 5 arms *c* may be engaged with the corresponding bracket, the other arm being engaged with an ear or bracket *t* at the adjacent end of the base.

When it is desired to renew a carbon-sheet, 10 the screw *p* is removed from the roller and the cover *k* is lifted, permitting the roller with its attached carbon-sheet to be removed and another inserted in place. When a new roller has so been inserted, the cover is 15 closed, engaging its pin *l* in the orifice *m* of the roller and the screw *p* is engaged in the corresponding end of the roller. When it is desired to unroll the carbon-sheet, the cover *k* is lifted, permitting the roller to be rotated 20 by the head of the screw *p* or otherwise. The cover is then closed, holding the roller in given position. It will be obvious that in this manner the roller has a rotatable adjustable connection with the base, the pin or stud 25 of the cover *k* engaging in either end of the orifice in the roller.

What I claim as my invention is—

1. In a manifolding device a base, a revolute roller upon which a carbon-sheet may be 30 wound, and brackets carrying said roller, one of said brackets provided with a cover, said cover being provided with means to engage the roller and hold it in a given position of adjustment.
- 35 2. In a manifolding device a base, means to hold a series of sheets or blanks thereupon, a revolute roller to carry a carbon-sheet; brackets at opposite ends of the shaft, said roller having an adjustable engagement in 40 said brackets, and a cover constructed with a pin or spur to hold the roller in a given position of adjustment.
- 45 3. In a manifolding device a base to hold a series of sheets or blanks, a revolute roller

to carry a carbon-sheet, and brackets to carry 45 said roller, said roller perforated at one end thereof and one of said brackets provided with a cover having a pin to enter the perforation of the roller.

4. In a manifolding device a base to hold a 50 series of sheets or blanks, a revolute carbon roller, brackets mounted upon the base to carry said roller, a reversible cover to fold either side uppermost when opened or closed to carry a series of sheets or blanks, and an 55 additional bracket on the side of the base adjacent to the cover, said cover having a hinged engagement with the adjacent brackets.

5. In a manifolding device a base to hold a 60 series of sheets or blanks, a revolute roller 65 to carry a carbon-sheet, and brackets to carry said roller, one of said brackets provided with a cover to close down over the adjacent end of the roller, said cover and roller provided with means to lock the roller in a given 70 position.

6. In a manifolding device a base to hold a 75 series of sheets or blanks, brackets supported upon said base, and a revolute roller to carry a carbon-sheet journaled in said brackets, one 80 of said brackets provided with a cover to close down over the adjacent end of the rolls, said cover provided with means to lock the roller in a given position.

7. In a manifolding device a base to hold a 75 series of sheets or blanks, a revolute roller to carry a carbon-sheet, brackets to carry said roller, and a holding-bar extending transversely of the base, and having an adjustable engagement at both ends thereof with said 80 brackets.

In testimony whereof I have signed this specification in the presence of two subscribing witnesses.

HENRY H. NORRINGTON.
